UNITED STATES PATENT OFFICE

JAMES P. MORLEY, OF LA PORTE, INDIANA, ASSIGNOR TO BASTIAN-MORLEY COMPANY, OF LA PORTE, INDIANA, A CORPORATION OF INDIANA

WATER-HEATER DRAIN

Application filed September 10, 1927. Serial No. 218,608.

My invention relates to water heaters and has to do especially with a novel means for draining water heaters in which the drain outlet is located at a point spaced from the 5 bottom of the storage tank.

In some instances, it is customary to employ water heaters embodying a storage tank with a separate heating element having suitable cold and hot water circulating connections therewith, and wherein the storage tank may be drained through the cold water inlet to the heating element. In such cases, it is desirable that the cold water inlet to the heating element be located within the storage tank and 10 at such a distance from its bottom that sediment, dirt, etc., which may collect thereon and thereabouts and which may be stirred up by the circulation of the cold water during the heating operation, will not be carried 15 to and pass through the heating element inlet to the interior of such element and impair its efficiency. With the inlet to the heating element, which may also serve as the tank drain outlet, located at a point above the tank bottom all of the water will not be drained from 20 the tank when the drain is opened unless otherwise provided for.

One of the objects of my invention is to provide an efficient automatic means for 30 effecting a rapid and substantially complete drainage of a water storage tank wherein the drain outlet is located at a point spaced from the bottom of the tank; and my invention is well adapted for solution of the problems 35 above referred to.

Another object is to provide a simple and inexpensive means for carrying out the foregoing object which may be readily applied to heaters already in use; and to this end, I employ 40 an automatically acting siphon carried by and cooperating with the main drain so as to continue the drain flow as the level of the water in the tank passes beneath the level of the drain outlet.

Other and further objects and advantages 45 will become apparent as this description progresses and by reference to the drawing wherein,—

Figure 1 is a vertical section of one form of 50 water heater embodying my invention;

Fig. 2 is an enlarged vertical section of a portion of the heater structure of Fig. 1, showing a form of siphon applied to the inwardly extending neck of the heating element which also serves as a drain outlet; 55

Fig. 3 is a plan view, partially in section, of the structure shown in Fig. 2, taken substantially on line 3—3 of that figure.

In the drawings, I have shown a form of heater to which my invention may be readily applied, but it is to be understood that my invention may be applied to other water heaters of different construction and wherein similar problems as to drainage exist. 60

The heater shown (Fig. 1) includes an outer wall 5 and an inner wall 6 with an insulating space 7 therebetween. The inner wall 6 is provided with a bottom 8 and a top 9 forming the water storage tank or reservoir 10. The tank is provided with the usual cold 70 water pipe 10^a and hot water pipe 10^b and is supported by a plurality of legs 11.

The tank bottom 8 is provided with a boss 12 adapted to receive a bushing 13 which, in turn, receives the threaded tubular neck portion 14 of the heating element 15 which may be referred to as a water spreader. The joint between the bushing 13 and the bottom 8 may be of the usual form while that between the bushing 13 and the spreader neck 14 is, preferably, formed by the cooperation of the tapered spreader seat 16, metal gasket 17 and the sharp-edged face 18 of the bushing 13 which provides a fluid tight joint which readily permits of detachment of the spreader 85 15. The spreader 15 is provided with a circulating member 19 supported by the spaced ribs 20 and carrying a circulating pipe 19^a. The lower part of the spreader is connected to an outlet or drain pipe 21 which passes through a suitable burner 22 to any convenient point and which is controlled by a suitable valve 23. 90

As the heater is used, dirt, sediment, etc., 95 may fall toward and be deposited upon the bottom 8. Cold water circulates through the spreader neck 14 beneath the member 19 where it is heated and it then circulates upwardly through the pipe 19^a to the top of the tank. During this action, there is a tendency 100

for the circulating cold water to stir up any sediment which may be on the bottom 8 and carry the same into the spreader 15 and impair its efficiency. To reduce this tendency to a minimum and to prevent dirt, sediment, etc., being carried from the bottom of the tank through the spreader neck into the spreader chamber 15^a, I extend the tubular spreader neck inwardly a considerable distance, so that its inlet 24 is at such a distance from the tank bottom 8 that the possibility of dirt, sediment, etc., on such bottom being stirred up and carried into the spreader by the circulating cold water is reduced to a minimum.

15 As hereinabove described, the draining of the tank takes place through the spreader neck, the spreader chamber 15^a and the drain pipe 21, and by extending the spreader neck as above described and as shown in Fig. 2, it will be readily seen that there will be a considerable amount of water in the bottom of the tank which will not drain unless otherwise provided for. I accomplish substantially complete drainage as follows: The upper edge of the spreader neck is provided with an opening 25 to receive a siphon, preferably, in the form of a tube 26, in such a manner that the base thereof does not extend above the upper edge of the spreader neck and the 20 siphon is contained within the vertical limits thereof. This tube may be fixed to the spreader neck by soldering or other suitable means. The short leg 26^a of the siphon extends downwardly along the outer surface of the tubular spreader neck to a point close to the tank bottom while its other and longer leg 26^b extends downwardly within the spreader neck to a point beneath the level of the inlet to the short leg. With this arrangement, assuming that the tank is empty, as the tank is filled, the water rises in the short leg 26^a as the level of the water rises in the tank and as this level approaches the upper edge of the spreader neck, the water rising 25 in the short leg 26^a will flow through the base of the siphon and down through the long leg 26^b thereof and expel the air therefrom. This action continues as the level of the water in the tank rises and as it rises in the spreader to and above the end of the long leg of the siphon. When the level of the water reaches the end of the long leg of the siphon, all of the air has been excluded therefrom and the tube is entirely filled with 30 water. In this manner the siphon 26 is automatically set and remains in such set condition until the tank is drained. To drain the tank, the valve 23 is opened and the water flows through the spreader inlet 24, spreader chamber 15^a, and drain pipe 21. As the level of the water in the tank is lowered to a point where it will not flow through the spreader neck opening 24, the flow is continued through the siphon 26 in a manner which will be well 35 understood and until the level of the water

has been reduced to the level of the inlet to the short siphon leg 26^a.

In the above manner, substantially all the water in the tank will be completely drained through the spreader and the drain pipe 21. The siphon is automatically set ready for the siphoning action as the tank is filled. It is of such character that it may be readily applied to heaters already in use. It eliminates the necessity of the use of additional drain pipes which would increase the number of parts of the apparatus and increase the cost.

70 While I have shown but one embodiment of my invention, it is to be understood that various changes and modifications may be made therein without departing from the spirit and scope of my invention as defined by the claims, which follow. For example, the siphon may be in the form of a U-shaped channel piece fixed upon the spreader neck 75 in such a manner that the walls of the spreader neck complete the tube. The bottom 8 may be convex instead of concave, as shown, and the short leg 26^a of the siphon extended close to the lowest part of the bottom, and the long siphon leg, of course, extended within the spreader neck to a point lower than the inlet 90 to the short siphon leg.

I claim:

1. In a water heater, a storage tank and a hollow drain member mounted in the bottom of said tank and extending inwardly to a point spaced therefrom, means for normally closing the drain member and a siphon carried by said member with its short leg extending exteriorly of said member to a point close to said tank bottom, and its longer leg extending interiorly of said member.

95 2. In a water heater, a storage tank and a hollow drain member mounted in the bottom of said tank and extending inwardly to a point spaced therefrom, means for normally closing the drain member, said member having a notch in its upper edge to receive the base of a siphon within its vertical limits, the short leg of which extends exteriorly of said member to a point near the bottom of said tank and its long leg extending interiorly of said member, said siphon being automatically rendered effective as the tank is filled 100 with water.

105 3. In a water heater, a storage tank, a drain pipe in the bottom of said tank, and extending upward into said tank, means for normally closing said drain pipe, and a siphon having its short leg extending adjacent the bottom of said tank and its long leg extending into said drain pipe.

110 4. In a water heater, a storage tank, a drain pipe in the bottom of said tank, and extending upward into said tank, means for normally closing said drain pipe, and a siphon having its short leg extending adjacent the bottom of said tank and its long leg extending into said drain pipe, said siphon be- 115 120 125 130

ing automatically rendered effective as the tank is filled with water.

5. In a water heater the combination of a storage tank, a heating element carried by said tank and having an inlet communicating with the interior thereof at a point spaced from the tank bottom, a drain pipe connected to said element and in communication with the interior of said tank through said inlet, and a siphon carried by said inlet for draining the water from the tank when the water level is reduced below said inlet.

10 6. In a water heater the combination of a storage tank, a heating element carried by said tank and having a hollow inlet portion extending through said bottom to receive the water at a point spaced from the tank bottom, a drain pipe connected to said element and adapted to drain water from said tank through said inlet portion, and a siphon carried within the vertical limits of said inlet portion with its short leg extending exteriorly of said portion to a point near the tank bottom and its longer leg extending interiorly of said portion to continue drainage as the level of the water is brought below the inlet to said element.

15 7. In a water heater the combination of a storage tank, a heating element carried by said tank and having a hollow inlet portion extending through said bottom to receive the water at a point spaced from the tank bottom, a drain pipe connected to said element and adapted to drain water from said tank through said inlet portion, and a siphon carried within the vertical limits of said inlet portion with its short leg extending exteriorly of said portion to a point near the tank bottom and its longer leg extending interiorly of said portion to continue drainage as the level of the water is brought below the inlet to said element, said siphon being automatically rendered effective by filling said tank with water to a point above said element inlet.

20 8. In a water heater, the combination of a storage tank, a heating element having an inlet pipe in communication with the interior of said tank at a point spaced from its bottom, a drain pipe connected to said element and to the interior of said tank through said inlet pipe for draining said tank to the level of the inlet to said inlet pipe, and a siphon carried by said inlet pipe and having its short leg extending exteriorly thereof adjacent the tank bottom and its longer leg extending within said inlet pipe for draining said tank as the level of the water therein falls below the level of the inlet to said inlet pipe.

25 9. In a water heater, the combination of a storage tank, a hollow tube adapted for draining water from said tank carried in one of the tank walls and having its inlet spaced from the tank bottom, means for normally closing the tube, said tube having a notch in its upper edge, a siphon carried by said

30 tube within said notch so that the base of said siphon does not extend above the upper edge of said tube, said siphon being arranged to drain the water from said tank when it has been reduced to and below the level of the entrance to said tube.

35 In testimony whereof, I have subscribed my name.

JAMES P. MORLEY.
